Primary Examiner — Kimberly Barnes(74) *Attorney, Agent, or Firm* — Joseph E. Maenner;
Maenner & Associates, LLC**CLAIM**

The ornamental design for a hunting mask, as shown and described.

DESCRIPTION

FIG. 1 is a perspective view of a hunting mask showing my new design.

FIG. 2 is a front elevational view thereof.

FIG. 3 is a rear elevational view thereof.

FIG. 4 is a right side elevational view thereof.

FIG. 5 is a left side elevational view thereof.

FIG. 6 is a top plan view thereof; and,

FIG. 7 is a bottom plan view thereof.

The broken lines in the drawings depicting a wearer's face represents environmental subject matter that forms no part of the claimed design. The remaining broken lines depict features or lines of stitching on the hunting mask that form no part of the claimed design.
